C. O. SISLER

ACID PROPORTIONING AND CONTROL SYSTEM FOR SULPHITE MILLS

Filed Jan. 24, 1927

UNITED STATES PATENT OFFICE.

CHARLES OLAND SISLER, OF SAULT STE. MARIE, ONTARIO, CANADA.

ACID PROPORTIONING AND CONTROL SYSTEM FOR SULPHITE MILLS.

Application filed January 24, 1927. Serial No. 163,276.

This invention relates to an acid proportioning and control system for sulphite mills, and the objects of the invention are to provide a simply constructed and durable means for pumping the hot relief liquor directly into the digesters from the moment that the digesters start to fill whereby a saving in steam is obtained and the heat of the liquor and gas is not lost in the cooling water of the liquor and gas coolers.

Further objects are to provide improved means whereby the hot relief liquor and gas from the digesters in the process of cooking can be mixed and proportioned with the cold acid from the storage tank, the resultant hot mixture, effecting considerable economy in the saving of steam, which would be required if the cold acid was pumped directly into the digesters, furthermore, this operation can be accomplished regardless of the pressure difference between the digesters.

Further objects are to provide an acid proportioning and control system of the character described, so arranged that the several parts and elements involved will more satisfactorily perform the functions required of them, resulting in higher efficiency and economy of operation.

A still further object is to provide a means for proportioning and controlling the temperature and strength of the cooking liquor from the storage tank.

With these and other objects in view the invention comprises an ejector member, the suction end of which is connected through a valve controlled pipe with the liquor storage tank, and the discharge end, of which is connected to the suction side of the filling pump of the system.

The ejector is also connected through a valve controlled pipe line with the top and side reliefs of the digesters, whereby it is possible to relieve hot liquor and gas or both from one or more of the digesters if more than two are installed, passing it through the nozzle of the ejector to the suction side of the filling pumps into the discharge line and valve controlled filling line back into the other digester. The passage of the relief liquor or gas which is usually

under pressure creates a partial vacuum in the suction side of the ejector.

Referring now to the drawings in which like characters of reference indicate correspondingly parts in each figure.

The figure illustrated is an elevation view of the system for sulphite mills.

Referring more particularly to the drawings in which a typical sulphite mill with two digesters are shown, this may be with the exception of my improvements considered as a standard construction of the average sulphite mill, and is already known in the art, the new and novel features of my invention and the manner of applying these features to the piping layout of the average sulphite mill is as follows and can be used in any sulphite mill with two or more digesters.

The features of my invention comprise a valve 10 communicating through a pipe line 11 and pipe line 12 with the top reliefs 13 and 14 controlled by valves 15 and 16 of the digesters 17 and 18. The line 11 controlled by the valve 10 also communicates through the line 12 and lines 19 and 20 with the side relief valves 21 and 22 for the digesters 17 and 18 respectively.

From the valve 10 a pipe line 23 is run to an ejector member 24. This pipe line terminates in a nozzle 25 in the throat of the ejector. The ejector is connected on its suction side 26 through a pipe 27 with the acid storage tank 28, while the discharge side 29 of the ejector is connected to the suction side 30 of the acid filling pump 31 in turn operated in any suitable and well-known manner by a motor 32. A check valve 33 is provided in the pipe 27 and connected to the suction side of the ejector, this check valve is so installed to permit the flow of acid from the liquor storage tank to the ejector, but does not permit reverse flow. A control valve 34 is also provided in the pipe 27 adapted to be operated preferably from the cooking floor, by remote control.

The remainder of the apparatus shown in the drawing comprise the pump discharge line 35 which pumps the cold liquor from the storage tank 28 into the top of the di-

gester or through the filling valve 36 into the bottom of the digester, through the steam line 37 the check valve 38 and pipe line as shown in the drawing.

5 Running from the pipe 12 is a pipe 38^a connecting with the separator, gas cooler, and reclaiming tower.

The pipe 39 valve controlled at 40 and 41 connects the pipe 12 with the steam main

10 37^a while the connections of the main are valve controlled in any well known manner by 42 and cooking valve 43. The line 35 is connected to the steam main by valve controlled lines 44 and 45, while a steam line 15 46 is provided for cleaning the strainers.

A separator is indicated by the numeral 47, connected through a controlled line 48 with the line 12, the line 48 being also pipe connected to the relief gas cooler 50, pro-

20 vided with a water intake 51 and water outlet 52. For the purpose of showing the operation and advantages of my system it is assumed that digester 17 is being cooked as is usual in the process, and that it is ready

25 for relieving liquor or gas or combined liquor or gas as the case may be, also that the digester 18 is being filled with wood chips the usual way would be to start the acid filling, and fill the digester 18 with cold 30 cooking liquor direct from the storage tank 28.

However, by the use of my system, it is now possible to relieve hot liquor or gas or both from digester 17 through either the 35 side relief valve 21 or top relief valve 15 into the pipe 12 and from there to the pipe 11 through the valve 10, pipe line 23 to the nozzle of the ejector 24. The relief liquor and gas passes from the discharge side 29 40 of the ejector to the suction side of the acid filling pump 31 and through the pump into the discharge line 35 through the filling valve 36 in the line 37 check valve 53 into the digester 18.

45 The creation of the vacuum above referred to in the ejector is not absolutely essential to the satisfactory operation of my system, as there is usually several feet of acid in the storage tank 28, which would force the 50 acid through the ejector to the impeller of the pump.

Accordingly if remote controlled valve 34 is opened cooking liquor will pass from the storage tank through said valve, through the 55 check valve 33 to the suction side of the ejector 24 and out of the discharge end 29 of the ejector to the suction piping of the pump to the impeller of the pump.

In the impeller part of the pump, this 60 acid is thoroughly mixed and intermingles with the relief liquor and gas from the pipe line 23. It is then discharged into the pump discharge line 35 and through the valves and piping outlined above into the digester 18.

65 By regulating the opening of the remote

controlled valve 34, it is possible to proportion and control the cooking liquor from the storage tank both for temperature and strength.

A test nipple 54 and a recording or indicating thermometer are provided on the pipe line 35, for the purpose of testing the strength and temperature of the acid respectively.

As many changes could be made in the 75 above construction, and many apparently widely different embodiments of my invention, within the scope of the claims, constructed without departing from the spirit or scope thereof, it is intended that all matter contained in the accompanying specifications and drawings shall be interpreted as 80 illustrative, and not in a limiting sense.

What I claim as my invention is:

1. In a sulphite mill, an acid proportioning and control system comprising in combination, digesters, a cooking liquor storage tank, an acid filling pump, valve controlled filling and discharging conduits for the digesters, a pipe common to said conduits, a 90 valve controlling said pipe, an ejector, communicating with the storage tank and the filling pump respectively and a pipe line connecting the ejector with the aforementioned control valve. 95

2. In a sulphite mill, an acid proportioning and control system, consisting of a pipe line, one end of which is in communication with the top and side relief piping of two or more digesters and controlled by means 100 of a valve, the other end of the said pipe line terminating in an ejector type of fitting.

3. In a system of the character described, a cooking liquor storage tank, an ejector, a 105 valve controlled pipe line connecting the ejector with said tank, a pump operatively connected to said ejector.

4. In a system of the character described, means for relieving the hot liquor from one 110 digester and passing it into the other digester, comprising an ejector communicating with the cooking liquor storage tank and with a pump respectively, a pipe line connected to the digesters, valve controls for 115 said pipe line, whereby on one or more of the digesters being relieved, the liquor is passed to the ejector and from the ejector to the pump and simultaneously the liquor is delivered from the storage tank to the pump, 120 from the pump through the filling valve, into the filling pipe line, and from there into the other digester.

5. The within described method of relieving liquor and gas from a digester which 125 consists in concentrating the relieved liquor, delivering it under control to an ejector, mixing and proportioning it with the cooking liquor, and then pumping it into another digester. 130

6. In a sulphite mill, the method of pumping the hot relief liquor directly into the digesters when the digesters begin to fill.

by causing the relieved liquor and gas to mix in suitable proportions with acid liquor, and then delivering the mixture under 10

7. The method of mixing in suitable proportions cold acid from a storage tank or the like with the hot relief liquor and gas from a digester in the process of cooking

In witness whereof I have hereunto set my hand.

CHARLES OLAND SISLER.
